DESIGN FOR A WATER COOLER CABINET

Edgar A. Self, Bronxville, N. Y., assignor to Cordley & Hayes, New York, N. Y., a corporation of New York

Application July 2, 1938, Serial No. 78,235

Term of patent 7 years

To all whom it may concern:

Be it known that I, Edgar A. Self, a citizen of the United States, residing at Bronxville, in the county of Westchester and State of New York, have invented a new, original, and ornamental Design for a Water Cooler Cabinet, of which the following is a specification, reference being had to the accompanying drawing, forming a part thereof.

Figure 1 is a perspective view of a water cooler cabinet embodying my new design; and

Figure 2 is a top plan view of said water cooler cabinet.

I claim:

The ornamental design for a water cooler cabinet, substantially as shown.

EDGAR A. SELF.
